V. J. WILLIAMS,
DOOR LATCH,
FILED JAN. 31, 1921.

FIG. 1.

FIG. 2.

INVENTOR
V. J. Williams
BY Mum Co.

ATTORNEYS

UNITED STATES PATENT OFFICE.

VIGER J. WILLIAMS, OF CHICAGO, ILLINOIS.

DOOR LATCH.

Application filed January 31, 1921. Serial No. 441,295.

To all whom it may concern:

Be it known that I, VIGER J. WILLIAMS, a citizen of the United States, and a resident of the city of Chicago, in the county of Cook and State of Illinois, have invented a new and useful Improvement in Door Latches, of which the following is a full, clear, and exact description.

My invention relates to improvements in door latches, and it consists in the combinations, constructions and arrangements herein described and claimed.

An object of my invention is to provide a door latch of relatively simple construction, which may be operated by pushing or pulling on the knob, instead of rotating the latter.

A further object of my invention is to provide a latch of the type described which, when applied to a door, will permit the latter to open when the knob is pushed toward the door, as, for instance, in a crowded theater in which a panic has taken place, thus obviating the necessity of turning the knob.

A further object of my invention is to provide a device of the type described which is positive in action, and which is not liable to easily get out of order.

Other objects and advantages will appear in the following specification, and the novel features of the invention will be particularly pointed out in the appended claims.

My invention is illustrated in the accompanying drawings, forming part of this application, in which—

Figure 1 is a sectional view on the line 1—1 of Figure 2, looking in the direction of the arrow, and

Figure 2 is a sectional view on the line 2—2 of Figure 1, looking in the direction of the arrow.

In carrying out my invention, I provide a metal casing 1, having a front flange 2 which may be made integral with the casing, or may be secured to it. The flange 2 is provided with the usual bolt opening 3, and also with openings to permit screws 4, to enter the door 5, which is mortised in the ordinary manner to receive the latch casing 1.

Arranged to extend through the bolt opening 3 is the latch bolt 6. The latter has a beveled end portion 7 and is slotted at 8 and 9 in the manner shown in Figure 1. A spring 10 bears at one end on that portion 55 of the bolt at the end of the slot 8, the other end of the spring being secured to a post

11 carried by the casing 1. The spring 10 normally tends to force the bolt forwardly. In Figure 1, I have shown the bolt in the recess 12 in the door jamb 13, a strike plate 14 of ordinary construction being used.

Arranged to slide transversely with respect to the casing is a shank 15, which is provided on its ends with knobs 16 and 17. This shank may be guided by plates 18 secured to the door, and is provided with a cam member 19 arranged to engage the bolt at the rear wall of the slot 9. The door 5 has a recess portion 20 arranged to receive the cam member 19.

From the foregoing description of the various parts of the device, the operation thereof may be readily understood. The door 5 is mortised in the manner stated, and the latch casing is inserted. The knobs 16 and 17 are removable from the shank, in order to permit the latter to pass through the guide plates 18. When the parts are in the position shown in Figure 2, it is only necessary to pull on the knob 16 to open the door, since the shank 15 will slide in the direction of the pull, and the cam member 19 will force the bolt rearwardly against the tension of the spring 10 until the outer edge of the bolt has cleared the strike plate 14, when the door will open. Obviously, the same result could be obtained by pushing on the knob 17. It must be seen that all that is necessary is to exert a force toward or away from the door, i. e., a pushing or pulling force, to open the door. Immediately on release of the knob, the spring 10 will force the bolt into position to engage the strike plate, the cam member 19 assuming the normal position shown in Figure 2.

I am aware that the movement of latch devices by cams is not broadly new. Such, however, is not my invention.

I claim:

1. In a latch, a casing having an opening, a latch bolt slidably disposed within the casing and adapted to extend through said opening, said latch bolt being provided with slots, a spring disposed in one of said slots and arranged to bear against a portion of said latch bolt, a pin carried by said casing and having connection with said spring, a shank arranged to pass through another of said slots in said latch bolt, said last named slot being provided with a straight rear wall 100 a cam member carried by said shank and arranged to engage the rear wall of said last

named slot in said latch bolt, knobs carried by said shank, and guide members for guiding the movement of said shank in a direction at right angles to the plane of movement of the latch bolt.

2. In a latch, a casing having an opening, a latch bolt slidably disposed within the casing and adapted to extend through said opening, said latch bolt being provided with 10 slots, a spring disposed in one of said slots and arranged to bear against a portion of said latch bolt, a pin carried by said casing and having connection with said spring, a shank arranged to pass through another of 15 said slots in said latch bolt, a cam member carried by said shank and arranged to engage a portion of said latch bolt, said cam member being arranged to extend laterally of said shank and being fashioned with a 20 beveled outer face, knobs carried by said shank, and guide members for guiding the movement of said shank in a direction at

right angles to the plane of movement of the latch bolt.

3. In a latch, a casing having an opening, 25 a latch bolt disposed within the casing and arranged to normally extend through said opening, said latch bolt having two slots therethrough intermediate the length of said bolt, a compression spring confined within 30 one of said slots and having one of its ends arranged to bear on the forward wall of the slot, a pin carried by the casing and arranged to extend into said last named slot in said bolt and support the opposite end 35 of said spring, a shank disposed through the remaining slot in said bolt transversely therethrough and slidably mounted in said casing, a cam member carried by said shank and arranged to engage the rear wall of said 40 last named slot when said shank is moved longitudinally and knobs disposed on the opposite ends of said shank.

VIGER J. WILLIAMS.
